MACHINE FOR OFFSETTING THE END COILS
OF SPRINGSDon D. Myers, Hempstead, N. Y., assignor to Kay
Manufacturing Corporation, Brooklyn, N. Y., a
corporation of New York

Application October 19, 1946, Serial No. 704,443

12 Claims. (Cl. 140—3)

1

This invention relates to machines for making spiral and the like springs and particularly to that type designed to coil wire fed to the machine into a spring, to tie or knot both end coils of the spring, to shape the end coils to a predetermined form and to nest the formed springs.

The invention is an improvement upon the well known machine disclosed in the patent to John F. Gail, No. 1,851,540 for making spiral springs. The improvement is directed primarily to the means for shaping the end coils simultaneously, while largely retaining the main features of the aforesaid patent. Hence only as much of said features is shown and described herein as is necessary for understanding of the invention, reference being hereby made to said patent which is intended to be incorporated herein for the detailed explanation and disclosure of the coiling, transferring and knotting mechanisms.

The present invention contemplates the provision of simple and dependable means for shaping the end coils of the springs to predetermined form immediately after the springs have been made and knotted and before they are nested and discharged from the machine, the form selected depending on the means used for connecting the springs and forming the spring unit of which the individual springs made by the machine constitute parts.

The invention further contemplates the provision of a number of pairs of cooperating jaws adapted to have coil-shaping inserts removably mounted thereon for engaging selected parts of the end coils of a spring to shape the end coils as desired, comparatively simple means being provided to operate the jaws at the proper times.

The invention further contemplates the provision of a spring making machine not only for making the springs and if desired for knotting the end coils thereof, but also embodying a station and mechanism at the station for so shaping the end coils that the springs may later be assembled in rows and interconnected by suitable helicals, clips or the like engaged with the end coils in a manner which is well known.

The invention further contemplates the provision of hydraulically operated end coil shaping jaws whereby selected parts of the end coils of the springs including the knotted parts thereof may be simultaneously shaped in the machine at a given station without interfering with the operation of the spring forming and knotting mechanisms.

The various objects of the invention will be clear from the description which follows and from the drawings, in which

2

Fig. 1 is a more or less diagrammatic front elevational view of the machine showing the stations at which and indicating the mechanisms by which the various operations are performed.

Fig. 2 is a fragmentary top plan view of the machine with parts broken away, showing particularly the arrangement of the hydraulic jaw operating mechanism.

Fig. 3 is a side elevational view of the jaw operating mechanism and of the means for depressing the operating rods for the spring transfer grippers.

Fig. 4 is an elevational view of a typical spiral spring made by the machine.

Fig. 5 is an end elevational view of the spring showing a typical form of the deformed or shaped end coil thereof.

Fig. 6 is a fragmentary foreshortened front elevational view of the jaws for shaping the end coils and of the transfer grippers showing the mechanism for reciprocating the grippers between stations.

Fig. 7 is a front elevational view similar to Fig. 6 but on an enlarged scale of the jaws and of the supporting means therefor showing the spring in place and the end coils thereof completely formed, shaped or offset.

Fig. 8 is a fragmentary front elevational view of one of the transfer grippers, the discharge chute and the means for insuring nesting of the completed springs in the chute and showing the retracted position of the gripper in dash-dot lines.

Fig. 9 is a vertical sectional view of the jaws and the hydraulic operating mechanism therefor taken on the line 9—9 of Fig. 2.

Fig. 10 is a rear elevational view partly in section of the pump controlling the hydraulic mechanism and of the operating mechanism for the pump.

Fig. 11 is a diagrammatic view of the hydraulic jaw operating system.

Fig. 12 is an enlarged side elevational view of one pair of end coil shaping jaws showing a portion of the operating cam therefor in section.

In the practical embodiment of the invention shown herein by way of example, the machine of the aforesaid Gail patent has been modified in the following main respects; first, by aligning the two knotting stations axially of the spring operated on thereby so that both of the end coils of the spring made by the coiler are knotted simultaneously at a single knotting station; second, by eliminating the sizing station of said patent and substituting end coil shaping mechanism at said station;

third, by transferring the finished spring to a chute by means of a spring transfer gripper; and fourth, by providing an arm responsive to reciprocation of the grippers for nesting the springs in the chute.

Accordingly, the machine which will now be described briefly before the detailed description, comprises a coiler 20 to which wire is fed in the usual manner by the wire feed rolls 21, 22, the coiler being of a well known type and being diagrammatically shown at the coiling station of Figs. 1 and 2. After the spring as 23 has been coiled and severed from the feed wire, it is transferred by a suitable spring gripper as 24 to the knotting station, where the end coils 25 and 26 of the spring are engaged by the knotters 27 and 28 respectively and the free ends of the end coils wrapped or tied to form knots as 29. The knotters are of any well known type such as are disclosed for example in the Gail Patents Nos. 1,851,540 or 1,681,728. While the knots are being tied, the gripper 24 returns to the coiling station and the succeeding gripper 30 returns to the knotting station, it being understood that all of the three grippers are connected by a carriage as 19 (Figs. 1 and 6) for simultaneous operation. The gripper 30 grips the knotted spring and transfers it to the forming station where the end coils 25 and 26 are shaped as desired (Figs. 5 and 7). For example, the indent 31 is formed at the knot 29 to prevent the knot from slipping out of place along the end coil. At the same time, the opposed outstanding offsets 32 and 33 for the reception of suitable parallel helicals or the like connections (not shown) are also formed, as well as the flattened side edge 34 opposite the knot.

The two mechanisms 35 and 36 for shaping the end coils are substantial duplicates of each other and include a pair of pivoted jaws each carrying a removable die insert cooperating with a suitably shaped insert in the other jaw, the jaws being operated by a cam ring through hydraulic reciprocating mechanism. The pump 37 (Figs. 2, 10 and 11) supplies fluid under pressure to the hydraulic mechanism. After the end coils have been shaped, the gripper 30 having returned to the knotting station, the gripper 38 grips the spring and on the advance of the grippers, deposits the spring in the chute 39 (Figs. 1 and 8) the hinged nesting rod 40 at the same time advancing the spring deposited in the chute during the previous movement of the gripper 38, into the nesting position shown by the nest 41 (Fig. 8) of springs.

In the detailed description of the machine which follows, the operating mechanisms for the main instrumentalities will be briefly described and the structure and operation of the end coil forming mechanism will be set forth in full. It being understood that the wire 42 advanced by the rollers 20, 21 is coiled into a spring by the coiler 20, it need merely be said that the coiler is operatively connected to the main shaft 43 of the machine by suitable intermediate connections not shown, which actuate the coiler at the proper time to make and to sever the spring. The gripper 24 which transfers the spring to the knotting station is operatively connected to the other grippers 30 and 38 by the reciprocating carriage 19, which is supported and guided by the fixed bars 18. To reciprocate the carriage and the grippers as a unit, the chain 44 (Figs. 1 and 6) is secured to a projection as 46 on the carriage as by means of suit-

able adjustable rods as 45 each fastened at one end to the chain and at the other end secured to the projection 46. The chain 44 passes about suitable rollers 17 pivotally supported by a fixed part of the machine, and is oscillated first in one direction and then in the other direction by the cam 48 (Fig. 6) on the main shaft 43, through the levers 49 and 50, one end 51 of the chain being secured to the outer end of the lever 49 and the other end 52 being secured to the outer end of the lever 50, directly if desired, or as shown through the intermediary links 54 and 53. A suitable spring as 55 secured to the chain and the lever 50 tensions the chain and forms a yieldable connection between the chain and the lever to permit overthrow of the cam, the spring yielding under excessive movement of the lever. The cam is so shaped that when that end of one lever which follows the cam is at the high part of the cam, the corresponding end of the other lever is at the low part of the cam whereby when one lever tensions the chain, the other releases the chain. Rotation of the main shaft 43 rotates the cam 48 causing oscillation of the levers 49 and 50 and reciprocation of the chain 44 and the carriage 19, thus moving the respective grippers 24, 30 and 38 as a unit between the pair of adjacent stations at which each gripper operates.

Each of the grippers includes a housing 56 suitably secured to the carriage 19 and slidably supporting a gripper-jaw operating rod 57 for vertical reciprocation therein, the rod being urged upwardly by the spring 58 within the housing. Rack teeth 59 at the lower end portion of the rod 57 engage the gear segments 60 at the upper ends of the gripper jaws 61, each of which jaws is pivotally supported by the housing 56 as at 62. Arranged at the upper ends of the rods 57 of the various grippers is the horizontally disposed bar 63 operative to depress the rods 57 simultaneously and thereby to open the jaws of the grippers and to release the springs held thereby. Vertical movement only is imparted to the bar 63 against which the upper ends of the rods or rollers 64 thereon are pressed by the springs 58. Such movement is given the bar 63 by means of the oscillating arm 65 (Figs. 2 and 3) projecting from the bar and fixed to the shaft 66, which shaft is suitably supported by a fixed bracket 67 and is oscillated by the arm 68 thereon through the cam rod 69. The spring 70 pulls the rod 69 into engagement with the cam 71 on the main shaft 43. At the time the carriage is at rest, the gripper jaws are closed upon the spring to be transferred, by the gripper spring 58 which moves the rod 57 upwardly into contact with the bar 63 which is then in its uppermost position. After the carriage 19 is moved to transfer the grippers and the springs engaged thereby to the next succeeding station and at the end of the movement of the carriage, the cam 71 becomes operative to depress the bar and the rods 57 thereby to open the gripper jaws and to release the springs. The gripper jaws remain open during the return movement of the grippers and carriage, whereafter the cam 71 releases the rod 69, permitting the spring 70 to raise the bar 63 into its uppermost position and to permit the gripper jaws to close, the operation being then repeated.

The spring made by the coiler is thus transferred by the gripper 24 to the knotting station from the coiling station. Since, as has been indicated, the knotting mechanism is of a well

known type, no description nor detailed illustration thereof is deemed necessary. It might be said that the knotters wrap the free end of each end coil of the spring 23 about an adjacent coil in the usual manner and that the knotters 27 and 28 are axially aligned with each other and with the axis of the spring operated upon (Fig. 2), whereby both end coils are knotted at the same time. Preferably, the knots are arranged at the extreme left of the spring as viewed in Figs. 7 and 8 to permit easy nesting of the finished springs. It will be understood that to make springs with free end coils, that is without tying knots on the end coils, the knotting mechanism and the knotting station as well as the gripper 30 may be omitted or rendered inoperative without affecting the operation of the end coil forming mechanism. From the knotting station, the spring is transferred by the gripper 30 to the station at which the end coils are shaped. The end coil forming mechanisms are axially aligned with each other and with the axis of the spring 23 at the forming station. Said mechanisms being substantially identical, a description of one will suffice for both.

In the forms of the end coils 25 and 26 shown herein as exemplary in Figs. 5 and 7, the originally circular end coils produced by the coiler are outwardly offset at two opposite points as at 32, 33, flattened at one point as 34 and indented at the knot 29. Hence four pairs of forming jaws are provided for shaping each end coil, the jaws 12, 13 forming the offset 32, the similar jaws 14, 15 forming the offset 33, the jaws 16, 17 forming the flat side 34 and the jaws 18, 19 forming the indent 31. To enable the jaws to operate upon springs of different sizes and to produce end coils of different shapes, each of the jaws is provided with a removable forming die of the required size and shape cooperating with a suitable removable die in the opposing jaw.

The various pairs of jaws are shown as circumferentially spaced apart 90° around the jaw holder 80 (Figs. 7 and 9) each pair of jaws being pivotally mounted on a pivot as 81 fixed in the jaw holder. As best seen in Fig. 12, a transverse groove 82 is made in the die holding end of each jaw, in which groove is removably secured as by means of a suitable screw or the like, a die 83 of the required shape to cooperate with the die of the cooperating jaw and to form a selected part of the end coil to the desired shape. The end coil is held in place at the end coil forming station for the forming operation by suitable adjustable stops as 84 arranged between adjacent pairs of jaws and secured to the jaw holder 80 as by the screws 85 passing through slots 86 in the stops. At its inner end, a projection 87 on the stop is provided with an angular outer surface 88 designed and shaped to engage or contact with the end coil prior to and during the forming operation at substantially a single point as 89 thereby to avoid distortion of the coil while it is being shaped. When the gripper 30 has completed the transfer of a spring 23 from the knotting station to the forming station and just before the release of the spring by said gripper, the jaw holder with the stops 84 and the jaws thereon is advanced axially of the spring toward the end coil, by suitable means soon to be described, a distance sufficient to carry the stop projections 87 inside of the end coil with the points 89 thereof in contact with circumferentially spaced points of the end coil. The forming jaws all being open during such advance of

the jaw holder, the end coil passes between the sets of cooperating jaws ready for the forming operation. Closing of the jaws presses the selected portions of the end coil between the dies 83 and shapes the coil.

Normally, the respective jaws of each pair of jaws are urged toward the open positions thereof by suitable compression springs such as the spring 90 arranged between and engaging the inner jaws 17 and 19, the similar spring 91 between the inner jaws 13 and 15, and the compression springs 92 between each of the outer jaws 12, 14, 16 and 18 and the adjacent portion of the jaw holder 80 (Fig. 9). Each of the jaws is elongated beyond its pivot 81 to provide the bifurcated extension as 93 on the outer jaw and the extension 94 on the inner jaw, the extension 94 being adapted to move into and out of the space between the branches of the bifurcated extension 93. The inner edge of the extension 93 is tapered downwardly and inwardly at one angle for part of its length as 96 beginning at the end of the extension and at a smaller angle for another part of its length as 97, the adjacent ends of the tapered lengths 96 and 97 being joined by a relatively short length 98 arranged at a greater angle than the length 96 and constituting an obstruction or bump between the lengths 96 and 97 for the purpose soon to appear. The outer edge of the extension 94 is similarly shaped to provide tapered lengths and a bump between the lengths. In the open positions of the jaws, the lengths 96 of the inner and outer jaws overlap as best seen in Fig. 9 thereby providing a relatively small wedge-shaped space as 99 between the cooperating jaws, the space being closed at one end by the bumps 98.

Passing into and moving through the space 99 and between the extensions 93 and 94 of the jaws is one of the segments of the segmental cam ring 100, which is provided with four such segments, one for each pair of jaws. Said ring is reciprocated longitudinally or in the direction of its axis and that of the jaw holder to force the cam segments between the jaw extensions and thereby to spread them apart and to close the jaws tightly upon the end coil after the jaw holder has been advanced to permit the stops 84 to engage the end coil of the spring 23 delivered to the jaws. On retraction of the cam ring, the segments thereof are carried back past the bumps 98, permitting the jaws to open under the pressure of the springs 90, 91 and 92. Since the length 97 of the jaw extension is at a smaller angle than the bump 98, the final parts of the closing movement and the initial part of the opening movement of the jaws are relatively slow as compared to the remainder of such movements, the bump 98 serving to permit acceleration of the jaw movements at the proper time.

Means are provided for preventing retraction of the jaw holder 80 before the jaws open and for reciprocating the cam ring 100. Said means comprises the plunger 101 secured to the piston shaft 102 and secured to the cam ring by the screw bolt 103 (Fig. 9). Self adjustment of the cam ring to the pressure thereon whereby the segments thereof may enter between and properly spread the jaw extensions, is attained by the engagement of the spherical projection 104 of the cam ring with the corresponding spherical depression 105 of the plunger. The under side of the head of the bolt 103 is similarly spherical to engage a second spherical depression 106 on the cam ring. By this arrangement, the cam ring

and the plunger reciprocate as a unit, while permitting the ring to adjust itself to the conditions it encounters, which may vary within narrow limits.

Circumferentially spaced around the flange 110 of the plunger are the series of screws 107 and pins 108, each pin being surrounded by a compression spring 109 which enters the enlarged opening 112 of the jaw holder, there being as many springs as are necessary to urge the plunger and the jaw holder apart with sufficient force to permit retraction of the cam ring into the space 98 without retracting the jaw holder. Each spring holding pin 108 has one end portion thereof fixed to the plunger and the other end portion thereof slidably inserted into the hole 111 of the jaw holder. The plunger is slidably fitted into the jaw holder, with the flange 110 slidable along the shanks of the screws 107, the head of each of which may move into and out of the enlarged hole 113 in the flange and the shank of which is secured to the jaw holder. The flange 110 is spaced sufficiently away from the adjacent end of the jaw holder to permit relative longitudinal motion therebetween, the flange and the jaw holder both being fitted into and slideable longitudinally in the sleeve 116 which is fixed to the housing 117 as by the screws 114. The jaw holder is suitably keyed to the sleeve to prevent relative rotation thereof, and the cam ring is also prevented from moving excessively relatively to the plunger by the pin 118 fixed to the plunger and entering loosely into the jaw holder.

It will now be seen that on reciprocation of the shaft 102, the plunger and the cam ring are reciprocated as a unit, but advance of the jaw holder relatively to the plunger by the springs 109 before a spring 23 is delivered to the forming station, is prevented by the engagement of the heads of the screws 107 with the bottom of the hole 113 in the plunger flange into which each head operates. When the plunger is advanced, the springs 109 become operative to advance the jaw holder by reason of the flange 110 leaving the screw heads and freeing them of the bottoms of the holes 113. Such advancing movement of the jaw holder is limited and halted by contact of the jaw holder with the discontinuous end wall 119 of the housing 117 as shown by the position of the jaw holder in Fig. 9, said end wall having suitable openings therein for the passage therethrough of the various jaws and of the stops 84. It will also be seen that the springs 109 exert such adequate advancing pressure upon the jaw holder as to hold it in contact with the wall 119 until the plunger has been retracted sufficiently to carry the flange 110 thereof into contact with the heads of the screws 107 whereafter retractive movement of the plunger against the screws causes retraction of the jaw holder but only after the cam ring has been retracted by the plunger and the forming jaws have opened. However, prior to the retraction of the jaw holder, the spring gripper 38 is closed upon the spring 23 at the forming station, whereby the spring is supported for transfer out of the machine after it has been released by the stops 84.

Preferably, though not necessarily, hydraulically operated means are provided for reciprocating the piston shaft 102. At that end of said shaft remote from the plunger, is secured the piston 120 reciprocating in the cylinder 121. Fluid under pressure is forced into the cylinder alternately through the pipes 122 and 123 at opposite ends of the cylinder, causing the piston to move

first in one direction and then in the opposite direction through a predetermined stroke. The fluid on the low pressure side of the piston returns to the double acting pump 37 (Figs. 10 and 11) comprising the piston 125 operating in the cylinder 124. To reciprocate the piston 125, its rod 127 is secured to one end of the connecting rod 128, the other end of which is secured to the crank 129 of any suitable type on the main shaft 10, 43 of the machine.

When the pump piston 125 moves toward the left as viewed in Fig. 11, the fluid is driven out of the pump cylinder on one side of the piston through the pipes 130 and 122 into the cylinders 121 and behind the pistons 120, thereby advancing said pistons and the piston shafts 102 to actuate the end coil forming jaws. As the high pressure fluid enters behind the pistons 120 the low pressure fluid on the other side of the pistons is drawn into the pump 37 through the pipes 123 and 131. When the pump piston 125 moves in the opposite direction or toward the right, the movement of the fluid is reversed, forcing fluid through the pipes 131 and 123 into the cylinders 121 in front of the pistons 120, while at the same time fluid behind the pistons is forced out of the cylinders 121 through the pipes 122 and 130 back into the pump cylinder 124, the operation being repeated on each reciprocation of the carriage 19, it being understood that movement of the plunger to close the jaws requires greater pressure than opposite movement.

Suitable automatic relief valves as 132 and 133 of any well known type are arranged respectively in the pipes 134 and 135, which communicate with the pipes 130 and 131. One valve as 132 serves to relieve excessive pressure in the system by permitting transfer of fluid between the pipes 130 and 134 as when the pump continues to operate in the direction to advance the plunger 101 after the forming jaws have been completely closed. Similarly, the valve 133 is adjusted to relieve excessive pressure in the system by permitting fluid to pass between the pipes 131 and 130 when the piston 125 continues to move toward the right after the plunger 101 has been retracted enough to carry its flange 110 into contact with the plate 139 at the end of the sleeve 116.

While hydraulic mechanism for operating the plunger 101 has herein been shown and described as the most efficient, simple and economical device for the purpose of reciprocating the plunger in the manner required, it will be understood that mechanical means may be substituted therefor if desirable or found convenient.

After the end coils of the spring 23 have been formed to the desired shape, the gripper 38 grips the spring and on release thereof by the jaw holder, the gripper transfers the spring out of the machine to the chute 39 where the finished spring is released (Figs. 1 and 8). The chute is provided with a constricted entrance portion 137 which slightly compresses the spring, said spring expanding as it is carried past the steps or shoulders 138 in the side walls of the chute. The spring thus deposited cannot move back into the chute entrance 137 because of the obstructing action of the shoulders 138. Simple means are provided to further advance the spring along the chute into interlocking engagement with the springs previously deposited therein, thereby to nest the springs into a loosely compacted mass for ease in handling and storage.

Said advancing means comprises the rod 40 pivoted at its upper end as 141 to and depend-

ing from a suitable bracket as 142 secured to the housing for the gripper 38. A fixed stop member 143 on the bracket and in the path of the rod limits the amount of swinging movement of the rod in a counterclockwise direction as viewed in Fig. 8. When the gripper 38 moves from the end coil forming station from the position shown in dash-dot lines in Fig. 8 to the full line position thereof shown, the rod 40 engages the spring 23 previously deposited in the chute and advances said spring to the nest of springs 41 to nest it with the other nested springs. At the same time, the gripper 38 replaces the spring thus nested with another. On the return movement of the gripper to the forming station, the lower end of the rod 40 engages the spring last deposited in the chute as the upper end of the rod moves past the spring whereby the rod is caused to swing clockwise during the return movement of the gripper, the shoulders 138 of the chute preventing the rod from pushing the spring back out of the chute. When the rod has been swung to such an angle that it can pass the spring, further movement of the gripper carries it past the spring and the rod drops back against the stop 143 ready to advance the next spring into the nesting position on the next movement of the gripper to repeat the operation.

The above description having included an explanation of the operation of the machine, no separate explanation of such operation is deemed necessary. It will be seen that I have provided relatively simple, efficient and adjustable mechanism for shaping the end coils of coil springs, which mechanism is preferably incorporated into and combined with a machine for making springs such as the Gail type of machine hereinbefore referred to, so that such machine is converted into one adapted to shape the end coils of the springs made thereby to provide a completely automatic machine operating to make, knot, shape and nest springs without separate handling or separate operations.

While certain specific embodiments of the invention have herein been shown and described, various obvious changes may be made therein within the spirit of the invention as defined in the appended claims.

I claim:

1. End coil shaping mechanism for a spring making machine comprising an axially reciprocating jaw holder, a plurality of pairs of circumferentially aligned cooperating jaws on the holder, a single pivot in the holder for each pair of jaws, each of the jaws being provided with an extension extending past the pivot, the adjacent edges of the extensions of a cooperating pair of jaws diverging in a direction away from the pivot, means for operating the jaws comprising a reciprocating cam ring provided with wedge shaped segments, one for each pair of jaws, and means for reciprocating the ring toward and from the jaw pivots to move the segments between the respective pairs of extensions, and a plurality of circumferentially aligned stops on the holder arranged to alternate with the pairs of jaws and movable with the holder as a unit into the interior of and into engagement with the end coil of a spring to support the end coil at points between the jaws.

2. End coil shaping mechanism for a spring making machine comprising a reciprocatingly radially grooved jaw holder, a series of jaws pivoted in circumferentially aligned pairs to and in the grooves of the holder, means on the holder and

75

movable therewith inside of the end coil of a spring to position said coil between the jaws of a pair of jaws and to hold said end coil and means to open and close each pair of jaws.

3. End coil shaping mechanism for a spring making machine comprising a jaw holder, a series of jaws pivoted in pairs to the holder, means on the holder to position the end coil of a spring between the jaws of a pair of jaws and to hold said end coil, and means to open and close each pair of jaws comprising an extension on each jaw, the extensions of each pair of jaws diverging to provide a wedge shaped space therebetween interrupted by opposed bumps on the extensions, springs normally maintaining the jaws open, wedge shaped means inserted into the space and reciprocable with the jaw holder as a unit when arranged at the end portions of the extensions beyond the bumps, and means to move the wedge shaped means axially of and relatively to the jaw holder in one direction past the bumps to close the jaws and in the opposite direction to release the jaws and thereby to permit the springs to open the jaws.

4. End coil shaping means for a spring making machine comprising a pair of pivoted spring-pressed normally open jaws, means for reciprocating said jaws bodily as a unit toward and from the end coil of a spring and means for closing the jaws, the reciprocating means including a jaw holder, a plunger axially aligned with the holder, means to reciprocate the plunger, means carried by the jaw holder and slidably engaging the plunger to move the jaw holder in one direction after a predetermined amount of movement of the plunger in said one direction, means carried by the plunger and slidably engaging the jaw holder to move the jaw holder in the opposite direction after a predetermined amount of movement of the plunger in the opposite direction and springs interposed between and urging the plunger and the jaw holder apart.

5. End coil shaping means for a spring making machine comprising a pair of pivoted spring-pressed normally open jaws, means for reciprocating said jaws bodily as a unit toward and from the end coil of a spring and means for closing the jaws, the reciprocating means including a jaw holder and a hydraulically operated reciprocating member having an operative connection to the jaw holder to reciprocate the holder through a lesser stroke than the stroke of the member.

6. End coil shaping means for a spring making machine comprising a pair of jaws spring-pressed toward an open position, a pivot for the jaws, each of the jaws having an extension thereon extending past the pivot and diverging away from the extension of the other jaw, a holder carrying the pivot, a housing for the holder, means for reciprocating the holder in the housing comprising a reciprocating member, and an operative connection between the member and the holder effective to reciprocate the holder through a lesser stroke than that of the member, and wedging means reciprocated by the member through part of the stroke thereof with the holder as a unit and through another part of the stroke thereof relatively to the holder and entering between the extensions of the jaws to operate the jaws.

7. End coil shaping means for a spring making machine comprising a pair of pivoted jaws swingable to a closed and to an open position and biased toward the open position, a reciprocating holder for the jaws, adjustable coil en-

11

gaging stops on the holder adjacent the jaws, reciprocating means operatively connected to the holder to move the holder therewith as a unit during the initial part of the stroke of said means in each direction, and means carried by the reciprocating means for operating the jaws during the remainder of each stroke of the reciprocating means.

8. End coil shaping means for a spring making machine comprising a plurality of pairs of movable jaws arranged in spaced relation, a shaping die removably carried by each jaw, a jaw holder carrying the jaws, an adjustable coil engaging stop on the holder between adjacent pairs of jaws, means for projecting the holder toward the end coil of a spring to carry the stops into engagement with the coil and to arrange the respective jaws of each pair of jaws on opposite sides of the coil, said means also operating to retract the holder after operation of the jaws, means to close the jaws of each pair of jaws upon the coil and thereby to shape the coil, and means to open the jaws prior to the retraction of the holder by the first mentioned means.

9. In a machine for shaping the end coils of a coil spring, a pair of similar opposed end coil shaping mechanisms each arranged to engage and distort one of the end coils and each comprising an axially movable jaw holder, circumferentially aligned pairs of pivoted jaws carried by the jaw holder, end coil engaging means carried by the jaw holder and movable axially therewith as a unit into the interior of the end coil to support said coil, and means movable as a unit with and axially of the jaw holder to operate the coil engaging means and movable relatively to the jaw holder to close the jaws upon the end coil.

10. End coil shaping means comprising reciprocating stops insertable axially and simultaneously into the end coils of a spring to hold the spring, a plurality of pairs of circumferentially spaced pivoted jaws movable first axially to embrace circumferentially spaced points of each of the end

12

coils and then movable radially to distort the coils to a predetermined shape and then retractable axially to release the distorted coils, and means to effect the movement of the coil distorting means, the coil distorting means comprising circumferentially spaced pairs of pivoted jaws each having a groove therein and a shaping die removably secured in the groove.

11. The machine of claim 10, the means for moving the coil distorting means comprising an axially reciprocating cam ring having segments each adapted to engage and to close a pair of jaws.

12. End coil shaping mechanism for a spring making machine comprising a jaw holder, a series of jaws pivoted in circumferentially aligned pairs to the holder, pivots on the holder for the jaws, a series of circumferentially spaced stops on the holder, each of said stops being arranged between and alternating with the pairs of jaws and being adapted to engage and to hold part of the end coil of a spring, a common jaw closing element engaging all of the pairs of jaws and means to move said element to operate the pairs of jaws simultaneously while the end coil is engaged by the stops.
